United States Patent Office.

MATTHIAS MARVIN, OF SALEM, OREGON.

Letters Patent No. 101,482, dated April 5, 1870.

IMPROVED SELF-TIGHTENING BUCKLE.

The Schedule referred to in these Letters Patent and making part of the same.

To all whom it may concern:

Be it known that I, MATTHIAS MARVIN, of Salem, in the county of Marion and State of Oregon, have invented a new and improved Self-tightening Buckle, with a convex ratchet catch in place of a tongue; and I do hereby declare that the following is a full and exact description of the said invention.

The nature of my invention consists in making a brass, iron, or other metal frame or rim of an oblong form, and of any width to suit the width of the strap, tug, band, or belt to be used.

At each end of the frame or rim is a slot, depressed from the main outer surface for the strap or belt to pass through.

In or near the middle of the frame or rim, and on each side, are small journal-boxes, into which is dropped or let the axle of the ratchet-catch.

The ratchet or substitute for a tongue to the ordinary buckle is also made of metal, and is shouldered on the under side to receive the end of the strap or belt, and to which the same is riveted.

The outer side near the fulcrum or axle is raised to

a half round surface and ratcheted, so as to prevent the slipping of the strap or belt.

The catch is hung by pins or axles in the journal-boxes of the rim, and works either way to loose or bind the strap or belt.

The strap or belt may be of leather, cotton, gutta-percha, or any other fibrous or pliable substance, and is further bound in its use by passing under the outer surface, of the frame or rim on each side of the ratchet, the ratchet rising slightly above the outer surface of the frame.

What I claim as my invention is—

1. A harness-buckle, provided with a shouldered and journaled vibrating ratchet with a hollow frame, having a strap slot at each end, a top slot, and journal-boxes or bearings, all as shown and described.

2. The arrangement of a ratchet with lever end, to vibrate in bearings formed on the inner sides of a buckle, in the manner set forth.
